Patented Jan. 3, 1922.

Inventor

Jesse W. Stapp

UNITED STATES PATENT OFFICE.

JESSE W. STAPP, OF FORT WORTH, TEXAS.

CLOTHES HANGER.

1,402,681.

Specification of Letters Patent. Patented Jan. 3, 1922.

Application filed August 24, 1921. Serial No. 494,934.

To all whom it may concern:

Be it known that I, JESSE W. STAPP, a citizen of the United States, residing at Fort Worth, in the county of Tarrant and State 5 of Texas, have invented certain new and useful Improvements in Clothes Hangers, of which the following is a specification.

This invention relates to improvements in clothes hangers and more particularly to a 10 hanger constructed of a single length of wire and adapted to support a coat, vest and trousers.

The primary object of the invention is to provide a clothes hanger constructed of a 15 single length of wire shaped and bent to form a place for containing each garment of a three piece suit.

Other objects of the invention will appear upon consideration of the following detail 20 description and accompanying drawings, wherein:—

The figure illustrates a perspective view of the hanger constructed in accordance with my invention.

25 Referring to the drawing by numerals, the main hanger 1 is constructed of the wire by shaping and bending the wire to form a relatively large hanger for receiving a coat, the inclined portions 2 receiving the shoulders 30 in the usual manner. The straight portion 3 which is ordinarily employed to receive the trousers, will in this instance, be used to receive the folded vest of the suit. Two portions of the wire are then arranged in 35 parallelism to form the arms 4 and 5 by bending the wire at the point 6 and forming a hook 7 by which the hanger may be supported. The bend at the point 6 forms a spring loop whereby the arms 4 and 5 will 40 normally spring outwardly away from each other and the terminal of the arm 4 carries a relatively small hanger 8 similar to the hanger 1 except that it is considerably smaller in dimensions, the straight portion 9 45 being adapted to receive the trousers by

hanging them over the straight portion in the well known manner. A hook member 10 formed on the terminal of the wire which forms the large hanger is adapted to engage the arm 4 to normally maintain the two arms 50 4 and 5 in close relative position when the hanger is in use. When the hook 10 is released, the arms 4 and 5 will spring outwardly and thus permit the elements constituting the hanger to be employed for hanging 55 the garment.

Minor changes may be made in the details of construction without departing from the spirit of the invention or the scope of the claim hereunto appended.

What is claimed is:—

A hanger of the character described comprising a single length of wire shaped to form a coat hanger having shoulder supporting members and a straight portion connecting the said members for providing a vest hanger, the said wire being shaped to form an arm connected at the junction of the said shoulder supporting element, a similar parallel arm formed in the wire by a semi-circular bend approximately intermediate the ends thereof, the said parallel arms being curved to form a supporting hook, one of the arms having its end portion shaped to provide a relatively small hanger similar to the 70 larger hanger but of shorter dimensions for forming a trousers hanger, and a hook formed by one terminal of the wire and adapted to engage one of the arms whereby the two arms will be held in relatively close 75 position against the spring action effected by the said semi-circular curved portion in the wire.
